FORM HANGER FOR CONCRETE SLAB
STRUCTURES

George B. Bosco, Chicago, Ill.

Application August 23, 1937, Serial No. 160,464

9 Claims. (Cl. 25—131.5)

This invention relates to hangers for suspending the temporary forms used in the construction of concrete slabs such as decks, floors, ceilings, and the like.

5 In such constructions, the concrete slab is usually supported by a plurality of horizontal permanent girders, beams, or joists which may be I-beams or other structural steel shapes. The temporary forms span the spaces between the 10 permanent beams and are suspended by hangers which embrace the beams.

The main objects of this invention are to provide a hanger for slab forms having an improved yoke adapted for mounting on top of the beam 15 and having improved suspenders coupled to the yoke and adapted to support the temporary forms; to provide improved supporting and spacing chairs for supporting the yoke and for spacing it from the top of the beam; to provide improved means for coupling the suspenders to the yoke so as to permit the suspenders to be removed from the embedded yoke after the concrete has set whereby the suspenders may be used over and over again; and to provide an improved hanger of this kind which is sturdy and which may be quickly and accurately assembled and applied even by unskilled labor.

Illustrative embodiments of this invention are shown in the accompanying drawings, where- 30 in:—

Figure 1 is a vertical section of a building structure showing one of the improved hangers;

Figure 2 is a perspective of the yoke part of the hanger shown in Figure 1;

35 Figure 3 is a sectional detail of a hanger and building structure showing a modified form of support and spacer for the yoke;

Figure 4 is an enlarged section of the yoke and spacer, the view being taken on the line 4—4 of Figure 3;

40 Figure 5 is a perspective of the yoke and spacers shown in Figures 3 and 4;

Figure 6 is a horizontal section taken on the line 6—6 of Figure 5;

45 Figure 7 is a view similar to Figure 1 but showing an adjustable yoke for accommodating beams of different widths;

Figure 8 is a perspective of the adjustable yoke shown in Figure 7; and

50 Figure 9 is a perspective of one end of the adjustable yoke shown in Figure 8 and its attached supporting and spacing leg.

In the construction herein shown, the improved hangers are used in connection with the construction of a concrete deck, floor, or ceil-

ing 1 which is supported on a plurality of joists, beams, or girders 2, only one of which is shown herein. These horizontal beams are usually arranged in substantially parallel spaced relation, and the spaces between the horizontal beams are 5 spanned by the temporary forms which are suspended from the beams by the improved hangers.

In the construction herein shown, the temporary forms comprise the usual decking 3 supported on horizontal joists 4 which are arranged in substantially parallel spaced relation and which are in turn supported by a plurality of pairs of stringers 5. The stringers of each pair are spaced apart so as to provide openings 6 15 through which the suspenders of the improved hangers extend.

In the construction shown in Figure 1, each of the improved hangers comprises a supporting yoke 7 supported on top of the beam and coupled at its ends to a pair of depending suspenders 8 which support the forms.

In the constructions shown in Figures 1, 2, 3, 5 and 6, the yoke is not adjustable and comprises a single bar which is preferably round in 25 cross-section and may be of any desired gauge which is sufficiently strong for the work involved. The yoke bar is substantially U-shaped so as to provide depending arms 9 which are externally threaded. These yokes are left embedded in the concrete deck after the concrete has set and, therefore, it is necessary to provide supporting and spacing means for raising the yokes above the lower surface of the deck. In the construction shown in Figures 1 and 2, such 35 supporting and spacing means comprises a pair of legs 10 which are preferably sheet metal stampings bent to substantially V-shape and being slightly longer than the depending arms 9 so as to raise the lower extremities of the 40 arms 9 above the plane of the lower face of the deck. As shown in Figure 2, the upper ends of the V-shaped legs 10 are bent outwardly away from each other so as to provide flanges 11 and 12. The flanges 11 are apertured so as to provide 45 openings 13 through which the ends 9 of the yoke extend. The flanges 12 are permanently secured to the yoke bar by spot welding as shown at 14 or by other suitable means.

In the construction shown in Figures 3, 4, 5 50 and 6, the supporting and spacing leg comprises a sheet metal stamping 15 of substantially inverted U-shape having strengthening ribs 16 in the leg portions thereof and having a depression 17 in the cross portion thereof forming a seat 55

for the yoke bar. The yoke bar may be spot welded to the legs 15 as shown at 18.

In the construction shown in Figures 7 and 8, the yoke portion of the hanger is adjustable 5 widthwise so as to be adapted for use in connection with structural shapes of different widths. The adjustable yoke comprises a comparatively long bar 19 and a relatively short bar 20, the ends of which are bent to form arms 21 and 22, 10 respectively, which are externally threaded similar to the arms 9. Attached to the outer end of the bar 19 is a supporting and spacing leg 23 which may be similar in construction to the legs 10 or, if desired, may be similar in construction 15 to the legs 15. The other leg of the adjustable yoke serves not only as a supporting and spacing leg but also serves as a coupling for slidably connecting the bars 19 and 20 together. As shown in Figures 7, 8 and 9, this coupling comprises a 20 substantially V-shaped sheet metal stamping 24 having a pair of openings 25 formed therein for slidably receiving the bar 19 and having a pair of openings 26 formed therein for receiving the short bar 20. Struck out from the leg 24 adjacent 25 the openings 26, are lugs 27 which are spot welded or otherwise rigidly secured to the bar 20. With this improved construction, the yoke may be adjusted as to width by merely sliding the leg 24 on the bar 19.

30 Each of the suspenders 8 is preferably of substantially the same construction as the tie element shown in my Patent No. 2,061,751, issued November 24, 1936, and in my copending application, Serial No. 151,582, filed July 2, 1937. It 35 comprises a bolt having a tapered head 28 and a flat shank 29. The tapered head 28 extends through an opening 30 in the decking 3 and has an internally threaded socket 31 for engagement with the threaded ends of the yoke. The shank 40 29 is of rectangular cross-section with threads 32 formed on only two of the opposed sides thereof. With this type of construction, a wrench may be easily applied to the flat sides of the shank without injury to the threads. Engaging 45 the threaded portions of the shanks 29 are wing nuts 33 having bearing portions 34 for engaging the lower faces of the stringers 5.

In operation, the suspenders are coupled to the yoke, and the yoke is then placed on top 50 of the beam with the suspenders depending therefrom. The entire weight of the forms is carried by the wing nuts 33, and these wing nuts may be readily adjusted for bringing the upper surface of the decking 3 to the required level which may 55 be either above, below, or in the plane of the upper surface of the beam.

In dismantling the forms after the concrete has set, the wing nuts 33 are removed so as to 60 permit dropping of the form parts, and the suspenders 8 are then unscrewed from the threaded ends of the yokes. The holes left in the bottom face of the concrete after the removal of the 65 suspenders 8 may be readily plugged with concrete. The yokes remain permanently embedded in the concrete.

Although but certain specific embodiments of 70 this invention have been herein shown and described, it will be understood that details of the constructions shown may be altered without departing from the spirit of the invention as defined by the following claims:—

I claim:

1. A hanger adapted to suspend temporary forms from a beam in the construction of concrete 75 slabs comprising a yoke adapted to remain em-

bedded in the slab after the concrete has set, legs mounted on said yoke for supporting said yoke on the beam and for spacing said yoke from the bottom face of the slab, a pair of depending suspenders threaded to the ends of said yoke so as to be adapted for removal of the suspenders after the concrete has set, and nuts on said suspenders for supporting the forms. 5

2. A hanger adapted to suspend temporary forms from a beam in the construction of concrete slabs comprising a yoke adapted to remain embedded in the slab after the concrete has set, said yoke being adjustable in width for straddling beams of various widths, legs attached to and depending from said yoke for supporting said yoke on and spaced above the beam, a pair of 10 suspenders detachably coupled to the ends of said yoke so as to permit removal of said suspenders after the concrete has set, and means on said suspenders for supporting the forms. 15

3. A hanger adapted to suspend temporary forms from a beam in the construction of concrete slabs comprising a yoke adapted to remain embedded in the slab after the concrete has set, said yoke being extensible and retractable for 20 accommodating beams of various widths, legs mounted on said yoke for supporting said yoke on the beam and for spacing said yoke from the bottom face of the slab, a pair of depending suspenders threaded to the ends of said yoke so as to 25 be adapted for removal of the suspenders after the concrete has set, and nuts on said suspenders for supporting the forms. 30

4. A hanger adapted to suspend temporary forms from a beam in the construction of concrete slabs comprising a yoke of substantially inverted U-shape having down-turned threaded ends, legs for supporting said yoke on the beam and spacing said yoke from the bottom face of the slab, a pair of depending suspenders having 35 threaded engagement with the ends of said yoke to permit removal of the suspenders after the concrete has set, and means on said suspenders for supporting the forms. 40

5. A hanger adapted to suspend temporary forms from a beam in the construction of concrete slabs comprising a yoke of substantially inverted U-shape having threaded ends, means for supporting said yoke on the beam, said supporting means being longer than said yoke ends so as 45 to position the extremities of said yoke above the plane of the top of the beam, a pair of depending suspenders having threaded engagement with the ends of said yoke to permit removal of the 50 suspenders after the concrete has set, and means on said suspenders for supporting the forms. 55

6. A hanger adapted to suspend temporary forms from a beam in the construction of concrete slabs comprising a yoke adapted to remain 60 embedded in the concrete and being of substantially inverted U-shape with threaded ends, a pair of depending suspenders at their upper ends threaded to the ends of said yoke and having threaded lower portions, and nuts on said lower 65 portions for supporting the forms, said nuts being vertically shiftable for adjusting the forms either by the rotation of said nuts relative to said suspenders or by the rotation of said suspenders relative to said yoke. 70

7. A hanger adapted to suspend temporary forms from a beam in the construction of concrete slabs comprising a yoke of substantially inverted U-shape adapted to remain embedded in the concrete, means on the ends of said yoke for 75

supporting the forms, and a pair of supporting legs welded to said yoke adjacent the ends thereof.

8. A hanger adapted to suspend temporary forms from a beam in the construction of concrete slabs comprising a yoke of substantially inverted U-shape adapted to remain embedded in the concrete, said yoke being in two sections slidably connected together to permit extension and contraction thereof, means on the ends of said yoke for supporting the forms, and a supporting leg mounted on said yoke and spot welded thereto.

9. A hanger adapted to suspend temporary forms from a beam in the construction of concrete slabs comprising a yoke adapted to remain embedded in the concrete, said yoke being in two sections to permit extension and contraction thereof, a pair of supporting legs mounted on said yoke, one of said legs serving as a coupling for slidably connecting said sections together, and suspenders on the ends of said yoke for supporting the forms.
